ATTORNEY

UNITED STATES PATENT OFFICE.

SANFORD D. LE CLAIR, OF SAN FRANCISCO, CALIFORNIA.

SCRAPER.

1,120,824.

Specification of Letters Patent. Patented Dec. 15, 1914.

Application filed August 11, 1913. Serial No. 784,116.

To all whom it may concern:

Be it known that I, SANFORD D. LE CLAIR, a citizen of the United States, residing at San Francisco, in the county of San Francisco and State of California, have invented new and useful Improvements in Scrapers, of which the following is a specification.

The object of the present invention is to provide an improved form of scraper for excavating operations, which will be simple and economical in construction, durable in use, having no loose parts liable to get out of order, and efficient in operation.

In the accompanying drawing, Figure 1 is a perspective view of my improved scraper looking from the front; Fig. 2 is a sectional view on the line 2—2 of Fig. 1; Fig. 3 is a cross-sectional view of a modified form of the scraper; Fig. 4 is a similar view 10 of a further modification; Fig. 5 is a view, similar to Fig. 2, showing a different method of uniting the two halves of the scraper; Fig. 6 is a broken perspective view of one of said halves in the latter construction, detached; Fig. 7 is a broken perspective view 20 of a further modification.

Referring to the drawing, 1 indicates my improved scraper, preferably made of two similar halves. Each half is formed from 30 a sheet metal blank having two parallel longer sides, the blank being bent through a little more than a right angle along a central line parallel with, and midway between, said sides. Ends of the two pieces are then 35 united so as to extend from each other substantially at right angles, said union being effected either by riveting over-lapping ends, as shown at 2 in Fig. 1, or bending inward said ends to form flanges 3, and 40 riveting said flanges together, as shown at 4 in Fig. 5. Said ends thus united are perforated to receive a ring 6 to which is attached a rear cable 7. The front ends have each a series of perforations 8, through any 45 desired perforations in which series can be passed rings 9 connected to an extending forwardly cable 10 which passes loosely through an eye 11 of a union 12, to another eye of which is secured a forwardly extending cable 13.

In use the cable 13 is wound around a drum rotated by a suitable engine and the

cable 7 passes around an idle pulley and is also operated by said engine. The scraper is thus self-regulating, for, when the cable 55 13 first advances, the earth which is scraped from the surface of the ground collects on the lower portion of the scraper and presses it downward into the ground, so that more and more earth is scraped thereby, until the 60 scrapings reach the level of the upper portion of the scraper. When it has been completely filled, and a sufficient quantity of earth is being conveyed thereby, the pressure on the upper portion of the scraper 65 prevents it digging into the ground and the scraper can ride easily over the surface of the ground to the point of destination. The degree to which the scraper tends to dig into the ground can be varied by properly 70 selecting the holes in the front end of the scraper to which the cable 13 is attached. When the scraper has arrived at the place to which the earth is desired to be conveyed, tension is removed from the cable 13 and 75 applied to the cable 7, and the scraper is drawn backward, immediately leaving its load, and traveling easily over the surface to the point from which it originally started.

In the modification of my invention 80 shown in Fig. 7 I may attach to the scraper at the apex or juncture of the two halves a cutter 18, formed of pieces of sheet metal, riveted together as shown at 19, and riveted as shown at 20 to the scraper. Said cutter 85 tends to cut and break up clods or lumps of earth.

Instead of bending the sheet metal of each half at a sharp angle, it may be bent in a curve as shown at 21 in Fig. 3, or the central portion of the half may be flat as shown at 22 in Fig. 4.

I claim:

1. A scraper consisting of two like halves secured together at their rear end and extending divergently forward, each half comprising upper and lower diverging portions extending both inwardly and forwardly.

2. A scraper, the sides of which extend divergently forward, each side consisting of a substantially V-shaped piece of metal, the sides of which extend divergently forward and respectively upward and downward.

3. A scraper, the sides of which extend

divergently forward, each side consisting of a substantially V-shaped piece of metal, the sides of which extend divergently forward and respectively upward and downward, and a cutter extending forwardly from the apex of the scraper in a substantially vertical plane.

In testimony whereof I have hereunto set my hand in the presence of two subscribing witnesses.

SANFORD D. LE CLAIR.
